UNITED STATES PATENT OFFICE.

OSCAR ROESEN, OF NEW YORK, N. Y., ASSIGNOR, BY DIRECT AND MESNE ASSIGNMENTS, TO ROBERT HOE AND CHARLES W. CARPENTER, OF SAME PLACE.

FOLDING MECHANISM.

SPECIFICATION forming part of Letters Patent No. 664,583, dated December 25, 1900.

Application filed January 22, 1900. Serial No. 2,246. (No model.)

To all whom it may concern:

Be it known that I, OSCAR ROESEN, a citizen of the United States, residing at New York, county of New York, and State of New York, have invented certain new and useful Improvements in Folding Mechanisms, fully described and represented in the following specification and the accompanying drawings, forming a part of the same.

10 This invention relates to certain improvements in the folding devices of printing-machines.

Fast rotary printing-machines as now generally constructed usually employ a rotating folding-cylinder which is provided with folding-blades, sheet-taking devices, and one member of a cutting device, the sheet-taking devices operating to seize the leading end of the web and advance it a given distance, after 15 which the cutting device operates to cut a sheet and the folding-off devices operate to fold the sheet off the cylinder. It sometimes occurs, however, that the cutting device fails to operate for various reasons, a common reason being that the grooved cutting-block which usually forms one member of the cutting device becomes worn. When the cutting device fails to operate, since the cylinder is rotated at a very rapid rate, the web is 20 liable to become wound around the folding-cylinder instead of being folded off, thus injuring the machine. Furthermore, when a product of associated webs or sheets which has been given one fold is given a fold by 25 the folding-cylinder which is transverse to the fold it has already received it frequently happens that the product will not be squarely and truly folded. This may be due to inaccuracy in setting the folding-blade and folding-roll- 30 ers or to the fact that the free edges of the associated sheets are more pliable and fold more readily than the creased edge, or to other reasons.

It is one of the objects of this invention to 35 provide means to coöperate with the folding-cylinder to prevent a sheet or web from being carried around the cylinder.

A further object of the invention is to provide means which will operate on the leading 40 edge of a folded sheet or web which is to re-

ceive a transverse fold from a folding-cylinder in such a way as to prevent the product from being folded out of true.

With these and other objects in view the invention consists in certain constructions 55 and in certain parts, improvements, and combinations, as will be hereinafter described and then specifically pointed out in the claims hereunto appended.

In the accompanying drawings, which form 60 a part of this specification, and in which like characters of reference indicate the same parts, Figure 1 is a front view of a folding-cylinder of ordinary construction, the improved device being shown in connection 65 therewith. Fig. 2 is a vertical cross-section of the construction shown in Fig. 1. Fig. 3 is a detail elevation of one of the parts of the cutting device.

Referring to the drawings, which illustrate 70 one embodiment of the invention, 1 indicates a folding-cylinder of ordinary construction, said cylinder being mounted on a shaft 2. The cylinder is provided with any usual form of folding devices, the devices in this instance 75 being shown as rotating blades 3, which co-operate with the usual folding-off rollers 4. The cylinder is further provided with any usual form of sheet-taking devices. In the construction shown these devices consist of 80 ordinary pins 5, said pins being thrown outward by springs 6, operating on rods 7, and being thrown inward by arms 8, connected to the pin-shafts 9, said arms coming in contact during the rotation of the cylinder with the 85 cam 10. The cylinder is also provided with one member of a cutting device, preferably a grooved cutting-block 11. This cutting-block is preferably provided with grooves 12, which are transverse to its cutting-groove, the 90 purpose of which will be hereinafter stated. The knife 13, which forms the other member of the cutting device, is mounted on the usual coöperating cylinder 14.

Suitable devices are provided to prevent 95 the web from being carried around the cylinder should the cutting device fail to operate or should the folding-off device fail to throw the sheet off the cylinder. While these devices may be varied considerably in construc- 100

tion, they preferably consist of a scraping-blade 15, said blade being provided with operating-prongs 16, which are arranged to run close to the circumference of the cylinder. 5 The blade 15 is secured to a supporting-bracket 17 in any suitable manner, as by screws 18, which pass through adjusting-slots 19 in the blade. The grooves 12 in the cutting-block are so arranged as to register with 10 the prongs 16 as the cylinder revolves. These grooves in the cutting-block therefore permit the scraping-prongs to be arranged closely to the cylinder, and if a sheet is not folded off for any reason its leading edge will be 15 caught by the prongs and prevented from being wound around the cylinder. The bracket 17 also carries a sheet-stopping device, the purpose of which is to act upon the edge of a product which is to be given a transverse 20 fold by the cylinder in such a way as to enable it to be truly folded. While this device may be variously constructed, it will preferably consist of two adjustable fingers 20, said fingers being adjustably secured to the 25 bracket in any suitable manner, as by screws 21, which pass through slots 22 in the fingers, these fingers being so located as to be struck by the leading edge of the product.

It is to be of course understood that the 30 sheet-stopping device and the scraping device hereinbefore described are so located as not to operate upon the material to be folded by the cylinder until after the sheet-taking devices which control its leading edge let go. 35 In other words, if the sheet-taking devices are pins the pins will be withdrawn from the leading edge of the product before it comes in contact with the scraping device or the stopping device. With the stopping device constructed 40 and operating as shown, it will be seen that if the folding mechanism is not producing a truly-folded product one or the other of the stops can be adjusted so as to retard one of the sides of the product, thus correcting 45 the inequality in the fold.

The construction by which the invention is carried into effect may be considerably varied. It is to be understood, therefore, that the invention is not to be limited to the exact 50 construction shown and described.

What is claimed is—

1. The combination with a pair of cutting-cylinders, one of which is provided with folding-off devices and with means for taking the 55 leading edge of a web, of means coöperating with said cylinder and operating upon the leading edge of the web to prevent the material to be folded from being carried around the cylinder, substantially as described.

2. The combination with a pair of cutting-cylinders, one of which is provided with a folding-blade and devices for taking the leading edge of a web, of a pair of rollers with which the folding-blade coöperates, and 65 means coöperating with said cylinder and acting upon the leading edge of the web to

prevent the material to be folded from being carried around the cylinder; substantially as described.

3. The combination with a pair of cutting-cylinders, one of which is provided with folding-off devices and with means for taking the leading edge of a web, of a scraping-blade located near the path of rotation of the cylinder and serving to prevent the web from being carried around the cylinder, substantially as described. 70

4. The combination with a pair of cutting-cylinders one of which is provided with a folding-blade and with means for taking the leading edge of a web, of a pair of rollers with which the folding-blade coöperates, and a scraping-blade located near the path of rotation of the cylinder and serving to prevent the web from being carried around the cylinder. 80

5. The combination with a pair of cutting-cylinders, one of which is provided with folding-off devices and with means for taking the leading edge of a web, of a stationary scraping-blade located near the path of rotation of the cylinder and serving to prevent the web from being carried around the cylinder, and means for adjusting the blade, substantially as described. 90

6. The combination with a pair of cutting-cylinders, one of which is provided with a folding-blade and with means for taking the leading edge of a web, of a pair of rollers with which said blade coöperates, a stationary scraping-blade located near the path of rotation of the cylinder and serving to prevent the web from being carried around the cylinder, and means for adjusting the blade. 100

7. The combination with a cylinder carrying folding-off devices, and one of the coöperating members of a cutting device, said member being grooved, of a scraping-blade having a series of points, the grooves of the cutting member being arranged to register 110 with the points of the scraping-blade as the cylinder revolves, substantially as described.

8. The combination with a cylinder having sheet-taking devices and folding-off devices, of a stop with which the leading edge of the product comes in contact after it has been released by the sheet-taking devices, substantially as described. 115

9. The combination with a cylinder having sheet-taking devices and folding-off devices, of an adjustable stop with which the leading edge of the product comes in contact after it has been released by the sheet-taking devices, substantially as described. 120

10. The combination with a cylinder having sheet-taking devices, folding-off devices and one member of a cutting device, of a scraping-blade for preventing the product from being carried around the cylinder, and a stop for the leading edge of the product, 125 substantially as described.

11. The combination with a cylinder hav-

ing sheet-taking devices, folding-off devices and one member of a cutting device, of an adjustable scraping-blade for preventing the product from being carried around the cylinder, and an adjustable stop, substantially as described.

5 In testimony whereof I have hereunto set

my hand in the presence of two subscribing witnesses.
